UNITED STATES PATENT OFFICE.

HARRY H. WIGGLESWORTH, OF PHILADELPHIA, PENNSYLVANIA, ASSIGNOR TO THE PHILADELPHIA DRYING MACHINERY COMPANY, OF PHILADELPHIA, PENNSYLVANIA, A CORPORATION OF PENNSYLVANIA.

AUTOMATIC DRIER FOR HOSIERY.

Application filed May 17, 1924. Serial No. 713,907.

To all whom it may concern:

Be it known that I, HARRY H. WIGGLESWORTH, a citizen of the United States, residing at Philadelphia, in the county of Philadelphia and State of Pennsylvania, have invented certain new and useful Improvements in Automatic Driers for Hosiery, of which the following is a specification, reference being had to the accompanying drawings.

10 This invention relates to machines for drying hosiery and kindred knitted articles, and it has for a primary object the provision of an automatic drier including a continuous guideway over which detached form carriers are traversed in intimate proximity while passing through a drying corridor, but spaced apart when exterior thereto for "clothing" and "stripping."

20 Another object is to provide an automatic drier for hosiery and other knitted articles characterized by great efficiency and economy in operation.

25 Other objects and attendant advantages associated with this invention will be later referred to, or become apparent from the following description; and said invention may be briefly defined as consisting in the novel features of construction, combinations and arrangements of parts hereinafter fully 30 set forth, and thereafter succinctly stated by the appended claims.

35 In the further disclosure of the invention reference is to be had to the accompanying sheets of explanatory drawings, constituting a part of this specification, and in which corresponding parts are distinguished by the same indices throughout the several views.

Fig. I, is a front elevation of a hosiery drying machine conventionally embodying this invention, with parts broken away to disclose certain underlying structural features.

Fig. II, is a plan view with a portion removed to better illustrate certain interior parts.

Fig. III, is a fragmentary sectional elevation taken on the line III-III in the preceding illustration.

50 Fig. IV, is a similar sectional view taken as indicated by the lines IV-IV in Fig. II.

Fig. V, is a more or less diagrammatic showing of a "booster" mechanism at the front of the machine.

Fig. VI, is a corresponding view of a

somewhat similar "booster" means located at 55 the rear of the machine.

Fig. VII, is a sectional elevation taken substantially as indicated by the line VII-VII, in Fig. II.

Fig. VIII, is a fragmentary sectional elevation illustrative of a slight modification hereinafter more particularly referred to.

Fig. IX, is a fragmentary sectional view taken as indicated by the line IX-IX in Fig. II.

Fig. X, is an enlarged detail view of one of the form carriers; and,

Fig. XI, is a vertical section of the preceding figure.

70 In the particular embodiment of the invention chosen for illustrating its characteristics and mode of operation, but which is not to be too conservatively regarded, the same embodies a framework of standard section verticals 12, braced by similar section 75 horizontals 13, and closed-in by thermo-insulated plates to provide an enclosure 14 in spaced relation to the floor level 15. This enclosure 14 is provided with a roof 16 having an inverted frusto-pyramidal deflector 80 17; for a purpose hereafter explained; and a bottom 18 having a rectangular guideway comprising parallel entry and exit avenues 19, 20 connected by a rear transfer-way 21; and said parallel avenues communicate, at 85 the front of the machine, with vertical ingress and egress openings 22, 23, respectively, in the enclosure wall, with which are associated other vertical auxiliary openings 24, 25, the purpose whereof will be here- 90 after fully set forth.

95 Conveniently mounted within the enclosure 14, and supported by standard section verticals 26, in spaced relation to the bottom 18, is a rectangular compartment 27 conventionally housing a plurality of radiators 28 through which the heating medium is circulated in accordance with ordinary practice. Appropriately supported in the upper part of the compartment 27 is a housing 29 for the horizontally rotatable fan 30; the shaft 31 whereof is journaled in a bearing 32, supported concentrically within the frusto-pyramidal deflector 17, aforesaid. 100 Rotary motion is imparted to the fan 30 through the medium of a miter-couple 33, driven by a horizontal countershaft 34, journaled in bearings 35, mounted on the roof 105

16 of the enclosure 14; and said countershaft is rotated by a belt drive 36 from any convenient source of power. Incidentally, it is noteworthy that the disposition of the compartment 27 within, and relatively spaced with respect to the interior of, the enclosure 12, affords a rectangular corridor 37, in which the actual drying operation is effected; while the arrangement of the fan housing 29 concentrically below the frusto-pyramidal deflector 17 ensures effective diffusion of the drying medium with a looped directional flow as clearly indicated by the arrows on Figs. I and III.

15 Referring to the drying forms 38, each of which is removably supported by an individual carrier-shoe 39 of irregular-hexagonal configuration in plan with an upstanding flange 40, Fig. XI, against which the form 38 is removably secured by means of a clamp-plate 41, and wing-nut bolts 42. Furthermore, the upstanding flange 40 and clamp-plate 41 are respectively butted by an angle section 43 and a Z-section 44, the upper lateral flanges whereof are relatively stepped to snugly close in the entry and exit avenues 19, 20, as well as the transfer-way 21, whereby wasteful escape of the heating medium through the bottom of the enclosure 14, is effectively prevented.

Still further it is to be noted that each carrier shoe 39 is fitted with a plurality of anti-friction or ball casters 45, and a centrally located stud 46 afforded guidance in a track 47, comprising co-planar angle-sections supported by, and braced to, the machine sub-structure in any convenient manner. This track 47, is configured to provide a raceway 48, Fig. IX, extending rearwards 40 from the front of the enclosure 14, in parallel relation and centrally below the entry and exit avenues 19, 20, as well as the transfer-way 21 hereinbefore referred to; and said track 47 is disposed co-planar with a 45 platform 49, constituting laterally projected boarding and stripping stations "B", "S", respectively, each having a hook-ended slot 50 therein. The stations "B" and "S" are each surrounded by an upstanding flange 51, for a purpose later on fully set forth, but it is to be particularly remarked that the hook-ended slot 50 is co-extensive with, and constitutes a part of the course traversed by the carrier shoe studs 46. In connection with 55 the platform 49, and the hook-ended slots 50 therein, it is noteworthy that the straight portions of the latter register with the ingress, egress, and auxiliary vertical openings 22-25 of the enclosure 14, as will be best understood by an examination of Fig. II, more particularly.

Having set forth the structural characteristics of the drying enclosure and the detached form carrier shoes 39 it is well to now describe the mechanism effective to progress

the series of forms 38 through the corridor 37, in abutting relation, as well as to traverse the same relatively spaced apart for stripping and clothing. This mechanism is operated through the medium of a coned pulley 52 on the countershaft 34, and a belt transmission 53, adapted to drive a reversely stepped pulley 54 secured on a horizontal shaft 55, journaled in bearings 56 mounted in the machine sub-framework. Incidentally it may be here noted that the thermo-insulated plates forming the walls of the enclosure 14 may be downwardly extended to the floor level 15, as shown in connection with the right-hand-half of Fig. I, to surround the mechanisms under consideration as well as to safeguard the wearing apparel of the attendants. Or, the said walls may terminate at the bottom level 18 with the lower portion of the framework surrounded by any other suitable screening material. On the shaft 55 aforesaid, is a pinion 57 in mesh with a train of gears 58, in turn operative to intermittently progress a vertically travelling endless chain 59, trained around sprocket wheels 59'—and provided at intervals with lateral lug links or projections 60 adapted to engage the studs 46 of consecutive carrier shoes 39, whereby the successive forms 38 are transferred from the entry avenue 19 to the exit avenue 20, in the manner hereafter fully explained. Furthermore the shaft 55, is provided with a worm 61 in gear with a worm wheel 62, splined on a short shaft 63 journaled in bearings 64, mounted in the machine sub-framework; and, said shaft 63 imparts progressive movement—

through the medium of an intermittent bevel couple 65—to a short vertical shaft 66 and sprocket-wheel 67 about which is trained a horizontally disposed endless-chain 68, similarly cooperative with an adjustable idler-sprocket 69, in the well known way. This endless-chain 68, is prevented from sagging by guidance along angle-section horizontal rails 70, and it is also fitted at intervals with lug links or vertical projections 71, functional to progress the forms 38 from the exit-avenue 20 to the entry-avenue 19 across the front of the machine as later on explained. At this point it is well to note that in the form of the invention shown by Figs. I, II, and VII more particularly the enclosure 14 closes in that portion of the platform 49 intermediate the stations "B" and "S" and hence the provision of the auxiliary openings 24, 25. On the other hand, and as shown by Fig. VIII the enclosure 14' may terminate relatively intermediate the runs of the endless chain 68, whereby the forms 38 are exposed during progression from station "S" to station "B", in contradistinction to transfer back—after being stripped—at "S" to reclothing location at "B".

In combination with the mechanism de-

- scribed for intermittently progressing the form carriers 39 at the front and rear of the machine, and in order to facilitate their transit along the entry and exit avenues 19, 20, respectively,—in close contact—use is made of the “booster” instrumentalities shown best by Figs. V and VI, and comprehensively designated 72 and 73. The former of these boosters—72—which is instrumental 5 in aiding progression through the entry avenue 19 comprises a cranked lever arm fulcrumed at 74 to a bracket 75 for horizontal oscillation, with the longer arm 76 thereof disposed to engage the stud 46 below each successive carrier shoe 39; and the shorter arm 77, inclined to provide a cam path with which co-operates a lateral wiper 78 on the shaft of a horizontally rotatable sprocket wheel 79 intermittently rotated by 10 the endless chain 68 aforesaid. This “booster” 72 is under the action of a contractile spring 80. On the other hand the “booster” 73, comprises a cranked lever arm, fulcrumed at 81, with its shorter arm 82 fitted with an antifriction roller 83 whereby it is horizontally rocked in opposition to a spring 84, while its longer arm 85 co-operates with the carrier shoe stud 46 of 15 each successive form 38, advanced from the transfer-way 21, into the exit avenue 20, as later on explained.
- Before proceeding further, particular attention is directed to the peculiar geometric configuration of the carrier shoes 39 which affords relatively angled front and heel ends 86, 87 respectively,—Figs. II, V and VI—as well as the curved portions 88, 89 of the hook-ended slot 50, whereby said carrier shoes receive a half-turn at each station “S” 20 and “B” so as to traverse the drying corridor 37 in uniform relation, as well as being temporarily retained in the regular planes—shown on Fig. II—at the aforesaid stations during the stripping and re-clothing periods.
- Having detailed the various structural features of the invention and their respective co-ordination, it will be obvious that when motion is imparted to the countershaft 34, the horizontal shaft 55 will be similarly rotated, whereby intermittent progressive movement will be communicated to the endless chains 59, 68 through the medium of the gear train 58 and bevel-couple 65, respectively. Now it will be readily comprehended that the hosiery forms 38 are moved through the drying corridor 37 concurrently with the entry of a clothed form at the station “B” and the withdrawal or ejection of another form at station “S” for stripping.
- The manner in which the form carriers 39 are successively withdrawn by the endless chain 68, stripped at “S,” and progressed over the platform 49, through the enclosure 14 by way of the auxiliary openings 25, 24 25 is thought to be so self-evident as not to necessitate further explanation. However it is desired to point out that each consecutive form 38, is transferred from station “S” to station “B” with four successive progressive movements intermediate the withdrawing and re-entering periods. Simultaneously with the entry of a form 38 reclothed with a fresh wet article to be dried at station “B,” another form with a dried article thereon is ejected at station “S.” Such relative movement of the forms 38 is reversed in the rear of the drying corridor 37, where each consecutive carrier 39 is transferred by a single movement from the entry avenue 19 to the exit avenue 20, and being automatically assisted into the latter by the booster 73. Now, when a form 38 emerges through the egress opening 23 at station “S” the stripper removes the dried hose and said form is transferred to station “B” by the four period progressions above referred to and reclothed with a wet hose. The succeeding intermittent movement transfers the reclothed form 38 into the entry avenue 19 through the ingress opening 22 with assistance of the booster 72. Obviously the successive progressive motions imparted will advance each form carrier 39 along the avenues 19, 20 a distance equal to their respective widths; and it is thought that the course of the series of forms 38 through the drying corridor 37 will be fully understood without further description.
- Finally it will be understood that various changes in the form, proportions, dimensions and minor details of the machine as an entirety, may be made without departing from the spirit of this invention or sacrificing any of its numerous advantages as an automatic and very efficient drier.
- Having thus described my invention, I claim:
1. A drier for hosiery and the like comprising a drying corridor, a continuous horizontal trackway therefor, a series of detached form carriers traversable over the trackway, boosting means adapted to intimately advance said form carriers along opposed directional lines, and coordinated means operative to transfer consecutive carriers from one line to the other with provision for exterior exposure and partial turning at definite positions.
  2. A drier for hosiery and the like comprising a rectangular drying corridor, a continuous horizontal trackway therefor, a series of detached form carriers traversable over the trackway, boosting means adapted to intimately advance said form carriers along parallel lines, and coordinated means operative to transfer consecutive carriers from one parallel line to the other with provision for exterior exposure and partial turning at definite positions.
  3. A drier for hosiery and the like com-

prising a rectangular drying corridor, a continuous horizontal trackway therefor, a series of detached form carriers traversable over the trackway, boosting means adapted to intimately advance said form carriers along parallel lines, means at one end of the parallel lines functional to advance consecutive carriers from one parallel line to the other, and coordinated means at the other 10 end to similarly transfer the carriers by successive stages with provision for exterior exposure and partial rotation at opposed points.

4. A drier for hosiery and the like comprising a rectangular drying corridor, a continuous horizontal trackway therefor, boosting means adapted to intimately advance said form carriers along parallel lines, means at one end of the parallel lines functional to advance consecutive carriers from one parallel line to the other, and coordinated means at the other end to similarly transfer the carriers by successive stages, the initial and final ones whereof are characterized by exterior exposure and partial turning.

5. A drier for hosiery and the like comprising a rectangular drying corridor, a continuous sub-planal trackway therefor, boosting means adapted to intimately advance said form carriers along parallel lines, means at one end of the parallel lines functional to advance consecutive carriers from one line to the other, coordinated means at the other end to similarly transfer the carriers by successive stages, the initial and final ones whereof are characterized by exterior exposure, and means effective to angularly position the forms during the stripping and reclothing periods.

6. A drier for hosiery and the like comprising a rectangular drying corridor, a continuous sub-planal trackway therefor, boosting means adapted to intimately advance said form carriers along parallel lines, means at one end of the parallel lines functional to advance consecutive carriers from one line to the other, coordinated means at the other end to similarly transfer the carriers by successive stages, the initial and final ones whereof are characterized by exterior exposure, and means effective to angularly position the forms during the stripping and reclothing periods, said means also serving to impart a half-turn to the carriers whereby the forms progress through the drying corridor with uniform disposition.

7. In a drying machine including an angular corridor having entry and exit avenues with a series of detached form carriers for progression therethrough, the combination of means for transferring consecutive carriers from the entry to the exit avenue, and a manipulator means actuated by each successive carrier during such

transference to boost the preceding carriers along the exit avenue.

8. In a drying machine including an angular corridor having entry and exit avenues with a series of detached form carriers for progression therethrough, the combination of means for transferring consecutive carriers from the entry to the exit avenue, and a lever-arm having an anti-friction roller thereon actuated by each successive carrier during such transference to boost the preceding carriers along the exit avenue. 75

9. In a drying machine including an angular corridor having entry and exit avenues with a series of detached form carriers for progression therethrough, the combination of means for transferring consecutive carriers from the entry to the exit avenue, and a spring influenced lever-arm carrying an anti-friction roller for cooperation with each successive carrier during such transference to boost the preceding carriers along the exit avenue. 80

10. In a drying machine including an angular corridor having entry and exit avenues with a series of detached form carriers for progression therethrough, the combination of an endless chain adapted to transfer consecutive carriers from the entry to the exit avenue, and a spring influenced lever-arm rocked by each successive carrier during such transference to boost the preceding carriers along the exit avenue. 90

11. In a drying machine including an angular corridor having exit and entry avenues with a series of detached form carriers for progression therethrough, the combination of mechanism for transferring consecutive carriers from the exit to the entry avenue, and a manipulator means actuated by said transfer mechanism to boost successive carriers into and along the entry avenue. 100

12. In a drying machine including an angular corridor having exit and entry avenues with a series of detached form carriers for progression therethrough, the combination of mechanism for transferring consecutive carriers from the exit to the entry avenue, and a lever-arm rockable by a wiper actuated by the transfer mechanism to boost successive carriers into and along the entry avenue. 110

13. In a drying machine including an angular corridor having exit and entry avenues with a series of detached form carriers for progression therethrough, the combination of mechanism for transferring consecutive carriers from the exit to the entry avenue, and a spring influenced lever-arm rockable by a rotary wiper actuated by the transfer mechanism to boost successive carriers into and along the entry avenue. 120

14. In a drying machine including an angular corridor having exit and entry avenues 125

with a series of detached form carriers for progression therethrough, the combination of an endless chain for intermittently transferring consecutive carriers from the exit to the entry avenue, a spring influenced lever-arm, and a rotatable wiper actuated by the endless chain to boost successive carriers into and along the entry avenue.

5 15. In a drying machine including an annular corridor having exit and entry avenues with a series of detached form carriers for progression therethrough, the combination of an endless chain for transferring consecutive carriers from the exit to the entry avenue in periodic stages, a spring influenced lever-arm, a rotatable wiper actuated by the endless chain to boost successive carriers into and along the entry avenue, and associated means whereby the carriers receive a half-turn after leaving the exit avenue and prior to passage into the entry avenue.

10 15. In a drying machine including an annular corridor having exit and entry avenues with a series of detached form carriers for progression therethrough, the combination of an endless chain for transferring consecutive carriers from the exit to the entry avenue in periodic stages, a spring influenced lever-arm, a rotatable wiper actuated by the endless chain to boost successive carriers into and along the entry avenue, and associated means whereby the carriers receive a half-turn after leaving the exit avenue and prior to passage into the entry avenue.

In testimony whereof, I have hereunto signed my name at Philadelphia, Pennsylvania, this 15th day of May, 1924.

HARRY H. WIGGLESWORTH.
